UNITED STATES PATENT OFFICE.

PIETRO VESCOVI, OF PUEBLO, COLORADO.

FOLDING SAFETY-BOAT.

1,082,833.

Specification of Letters Patent.

Patented Dec. 30, 1913.

Application filed March 2, 1912. Serial No. 681,204.

To all whom it may concern:

Be it known that I, PIETRO VESCOVI, citizen of Italy, residing at Pueblo, Colorado, have invented certain new and useful Improvements in Folding Safety-Boats, of which the following is a specification.

My invention relates to a folding safety boat; and the objects of my invention are to adapt air tight compartments with a boat construction to produce a bathing, hunting and portable safety boat in the combination in which the parts are arranged. I attain these objects by means of the mechanism illustrated in the accompanying drawings, in which,

Figure 1 is a side view in elevation of said boat; Fig. 2 is a top plan view; Fig. 3 is a perspective view and Fig. 4 is a broken sectional view giving detail of joint construction.

Similar numerals refer to similar parts throughout the several drawings.

A boat frame construction primarily is composed of parts 1 and 2 attached by hinged means 10. A lock piece 11 extending beneath the frame in L shape is attached to part 2 on the frame by bolt means 12, and may be adjusted to the part 1 by bolt means 13 provided with thumb screw. At the top and bottom in the center of the construction are cross pieces 8 and 9 which form a close contact when the boat is extended. At and near each end of the frame construction is provided a water tight compartment 5 with supporting cross bar 6 adapted to constitute a seat. On the front part 1 attached outside of the frame work on each side is an air tight compartment 3; and on the rear part 2 outside of the frame work is attached an air tight compartment 4. Rowlocks 14 are provided in which oars may be used but other means of propelling such boat may be used without interfering with my invention.

It will be observed that the front air tight chambers 3 are in a triangular form with the base near the middle of the boat, and that the rear air tight chambers 4 are in like manner triangular in form with the broad part or base at the rear end of the boat. The spaces 15 and 16 between the seats 6 are not necessarily floored but may be if so desired.

By this construction I have found the greatest resistance to tipping of the boat, and, at the same time, for the space used, the greatest sustaining area of the air tight compartments; and the part of the novelty in my device is in placing the air tight compartments outside of the frame work of the boat and at all times bearing part of the load, thus constituting a difference from the ordinarily constructed life or safety boat.

By means of the hinged construction the boat may be folded over so that the tops of parts 1 and 2 rest together and thus occupy a less space and be more readily adapted to transportation from place to place, and by the simple means of rendering the two parts rigid the boat may be quickly placed in position for use. If the occupant desires to protect himself from water, he may do so by using tarpaulin or other waterproof means spread over and extending over the spaces 15 and 16 and attaching the same to the sides 1 and 2 and the seats 6.

Primarily my device is adapted to a safety bathing or surf boat and as a portable hunting boat.

I am aware that air tight compartment boats have been constructed and I do not claim the same broadly, but

What I do claim is:—

In a device of the character described the combination of a boat frame divided into two parts connected by hinged means, a plate adapted by bolt and screw means to make the two parts when connected rigid, air chambers attached to the exterior of the front part of the boat construction triangular in form with the greatest area near the center of the boat construction, air chambers attached on the exterior of the rear portion of said boat construction with the greatest area at the rear of the same, and water tight compartment disposed in each end of said boat frame construction, all substantially as set forth.

Witness my signature.

PIETRO VESCOVI.
